TIMBER BLASTING DEVICE

Leonard H. Sawyer, Royal, Nebr.

Application March 23, 1937, Serial No. 132,628

1 Claim. (Cl. 102—6)

This invention relates to certain new and useful improvements in timber, log and post blasting devices and appliances; and the primary object of the invention is to generally and structurally improve upon devices of this type by providing a specifically distinct insert or plug expressly designed to more satisfactorily perform the function for which it is intended and to make more efficient the splitting and rending of stumps, logs, and analogous timber.

As implied by the preceding introductory paragraph, I am sufficiently conversant with the prior state of the art to realize that different types of blasting plugs have been perfected with a view toward concentrating the explosive power of the charge at a point of vantage within the vicinity of the heart or core of the timber being acted on. It follows, therefore, that in reducing to actual practice the specific principles of the present invention, I have perfected an unusually simple and convenient self-lodging plug adapted to effectively accommodate the powder charge, and to substantially regulate the discharge of the exploding force in such a way that the rending power is focused at the extreme inner end of the device, where it is most effective to accomplish the desired results.

Other objects, features and advantages of the invention will become more readily apparent from the following description and accompanying illustrative drawings.

In the drawings, wherein like numerals are employed to designate corresponding mechanical details throughout the views:

Figure 1 is an elevational view of the complete device ready to receive the charge.

Figure 2 is a central longitudinal sectional view taken approximately on the plane of the line 2—2 of Figure 1.

Figure 3 is a horizontal section on the line 3—3 of Figure 1.

Figure 4 is a horizontal section through the inner end of the device, the section being on the line 4—4 of Figure 1.

Figure 5 is a view on a slightly reduced scale, the section being on the line 5—5 of Figure 4.

Figure 6 is a detail view of the closing plug for the combustion chamber.

Referring now to the drawings by distinguishing reference characters, it will be observed that the major part of the implement is denoted by the numeral 7 and this is in the nature of a suitable metal shaft some 13 inches or more in length, under average or normal conditions.

55 This is a body substantially cylindrical in cross-

sectional form and the inner end thereof is bored to provide an axial centrally arranged socket, properly elongated, said socket being denoted by the numeral 8 and constituting the charge receiving chamber as well as the combustion or explosive chamber. Leading into the inner end of this pocket or chamber 8 is a somewhat diagonal passage 9 to introduce the inner end of the slow burning fuse (not shown). This fuse passage or opening 9 registers with a groove 10 extending longitudinally in one side of the body to accommodate a portion of the fuse. The fuse accommodation channel or groove 10 extends into a tool hole 11 formed transversely of the outer end portion of the body 7. This hole 11 serves to accommodate a removable rod which is used as a handle to turn the device into the log or other object to be blasted. It is centrally located and serves as an indicator usable in association with the diametrically opposite holes 12 formed in the inner end portion of the plug 7 and intersecting the combustion chamber 8. The extreme inner ends of these opposed holes 12 are beveled outwardly, as indicated at the point 13, to substantially match the substantially V-shaped inner end of the closing plug 14. That is to say, the closing plug has beveled surfaces forming a sort of a wedge, as indicated at 15, and these surfaces coincide with the surfaces 13 when the plug is properly inserted flush with the adjacent end of the main plug 7, as shown to advantage in Figure 2.

The numeral 16 designates a spiral cutting and imbedding thread formed on the inner end portion of the plug or body 7 to facilitate placement and secure anchorage.

In loading the blasting plug, a piece of slow burning fuse some 6 inches long is inserted at one end in the fuse hole 9 so that it extends into the combustion chamber 8. The outer end of the fuse is pressed into the groove 10 where it is protected and substantially flush with the circumferential surface of the plug 7. Thus, when the plug is threaded into place, it does not interfere with or dislodge the fuse from said channel or groove 10. Next, the threaded or inner end of the plug is turned up, that is, held up and with the thumb covering one of the holes 12, the powder is poured into the other hole to fill or partly fill the chamber 8. Next, these two holes 12 are plugged with paper or the like (not shown) to close them and to maintain the powder in the combustion chamber in readiness for the explosion.

In preparing the log for insertion of the device, an auger is used to drill or bore a hole in

the log, stump, or other object to be blasted. Experience and judgment must be called upon to determine how deep the hole is to be augered according to the cross-sectional dimension of the timber to be blasted. With large timbers the device must be screwed into the augered hole clear up to the point 11, as the purpose of the invention is to focus the explosion deep in the timber to insure effective results. A handle-bar 5 or similar device is inserted through the hole 11 and the device is threaded into the hole. Preparatory to this, however, the closing plug 14 has been placed in position and welded or otherwise secured temporarily in place.

10 The sharp edged screwing or feeding thread 16 insures proper lodging of the device in the drilled hole. Moreover, the threads cooperate with the wall of the hole to maintain the plug securely anchored and to avoid escape of pressure 15 around the peripheral portion of said plug. No special retaining devices or blocking is needed to secure the device in place, as the threads serve equally well to accomplish the desired results. By making the hole 11 in the same radial direction as the holes 12, it can be determined by positioning it either up, down, or to one side, as to what position the holes 12 have in the center or core of the log. Inasmuch as it is desired to direct the explosive forces in the most advantageous manner in relation to the cross grain of the wood, it is evident that it is important to properly "spot" the openings 12 to accomplish this result. The position of the hole 11 at the outer end therefore determines the exploding positions 20 of the holes 12 in the log. Hence, when the fuse is fired and explosion takes place, the force is expended first against the beveled deflecting surfaces 15 of the closing plug 14, whereupon the forces escape more or less equally through diametrically opposed holes 12, thus concentrating the power of the explosion at the point desired.

25 It is believed that a blasting plug of this type is structurally ingenious, efficient, aptly fitted for the purposes intended, easy to place in position 30 and remove, and otherwise well adapted to insure

predetermined explosive results. It is unnecessary, however, to delve into the commercial aspects of the invention, for it is believed that the points of advantage are sufficiently self evident to justify unqualified endorsement by the trade. 5

It is thought that the description taken in connection with the drawings will enable a clear understanding of the invention to be had. Therefore, a more lengthy description is thought unnecessary. 10

15 While the preferred embodiment of the invention has been shown and described, it is to be understood that minor changes coming within the field of invention claimed may be resorted to if desired.

15 I claim:

20 A blasting device of the class described comprising an elongated member of circular shape in cross section and having a centrally arranged bore extending from its inner end to an intermediate point of the member and providing a powder receiving chamber, a spiral thread forming rib on the exterior circumference of said member, said rib being of V-shape in cross section 25 and extending from the inner end of the member to an intermediate point thereof, the outer end of the member having a transverse hole therein and the inner end having a single pair of diametrically opposite arranged holes therein 30 communicating with the bore and slightly spaced from the inner end of the member, said holes extending in the same radial direction as the first-mentioned hole, whereby the first-mentioned hole acts as indicating means for the pair of holes as well as a handle receiving hole, a 35 plug closing the inner end of the member and having its inner end of wedge shape and the pair of holes each having its inner side walls sloping outwardly towards the inner end of the member and these sloping walls forming continuations of the sloping walls of the wedge-shaped part of the plug and said member having a passage therein 40 leading into the closed end of the bore for receiving a fuse.

LEONARD H. SAWYER. 45
